UNITED STATES PATENT OFFICE.

FRANK M. SLOUGH, OF ROCHESTER, NEW YORK, ASSIGNOR TO THE STROMBERG-CARLSON TELEPHONE MFG. CO., OF ROCHESTER, NEW YORK, A CORPORATION OF NEW YORK.

AUTOMATIC EXCHANGE SYSTEM.

Application filed December 24, 1917. Serial No. 208,622.

My invention relates to automatic telephone systems, wherein the act of a subscriber in operating a current commutating device at the substation is used to operate 5 switch mechanisms at a central office where the telephone lines leading to the various telephone substation terminate, the said switch mechanisms operating to complete a telephonic connection between the said subscriber's line and the line of a subscriber with whom it is desired to converse.

It is an object of my invention to accomplish the connection between the subscribers' lines by the use of mechanism and electrical 15 circuits having positiveness of operation and simplicity of design, as well as to be capable of being inexpensively installed.

It is a further object of my invention to accomplish the aforesaid object by the use 20 of connection setting-up-mechanism which will be common to a large number of subscribers, and to furthermore provide means whereby the setting-up-mechanism will be in use during but a small portion of the time involved in the use of a telephone from which 25 a call originates.

It is another object of my invention to provide a plurality of the aforesaid setting-up-mechanisms, and means whereby a calling 30 subscriber secures for a brief time the sole use of such mechanism, the said mechanism being thereafter discharged from the use of the said subscriber, and to provide means whereby the said setting-up-mechanism 35 thereafter reverts to the common use.

It is a further object of my invention to provide a novel means of completing the connection between connected subscribers' 40 lines by the use of a switch, preferably non-rotary in character, and upon which the connection can be made almost instantly.

Other objects of my invention and the invention itself will be apparent to those skilled in the art to which it appertains from 45 a description of the same which follows, and which reference is had to the drawings forming a part of this specification and in which:—

Fig. 1 shows several incoming telephone 50 lines together with diagrammatic representations of the apparatus at the subscribers' stations, and apparatus and circuits of a connection switch involved in extending a telephonic connection from one subscriber's station to another, the said connection switch

being common to a large number of telephone lines, and having calling and called switching terminals together with co-operating switch terminals for interconnecting link circuits associated with the said connection 60 switch. Controlling apparatus for the said connection switch is also indicated in this figure.

Fig. 2 shows extensions from the line circuits illustrated in Fig. 1 connected to 65 switch terminals of a connection switch whereby any of the lines initiating a call may be connected to a non-busy trunk circuit leading to an idle dialing or setting-up circuit. The mechanical structure of the connection switch, the circuits of which are 70 shown in Fig. 2 is much the same as the connection switch shown in Fig. 1, and illustrated in Fig. 5.

Figs. 3 and 4 together illustrate the apparatus and circuits of a dialing or setting-up-mechanism comprising as shown in Fig. 3 a step-by-step switch, controlling magnets therefor, and relay contacts for the said 75 relays controlled by the said step-by-step switch. Relays and circuits associated with the relays and circuits of Fig. 3 are shown in Fig. 4.

Fig. 5 shows some of the mechanical structure of such a connection switch, as has been referred to in connection with the drawings of Figs. 1 and 2, and Figs. 6, 7 and 8 show details in the various stages of operation of 80 portions of the structure of the connection 85 switch of Fig. 5.

The connection switch which is illustrated in the drawings and which I prefer to use, although other forms of switch may be used, is that illustrated and described in my Patent 1,363,364, granted December 28, 1920, 90 and for a fuller description of the operation of the switch indicated in the drawings of the embodiment illustrated herein, reference 95 may be had to the disclosure in the said patent.

The system of my invention will now be 100 described in detail, the various apparatus and circuits involved in the setting up of a connection between two subscribers' stations and the restoring of the apparatus and circuits involved in the said connection being so described.

Referring to Fig. 1, at A¹, I show a telephone set comprising telephonic transmission apparatus, and a current commutator in 105 110

the form of an automatic dial interrupter at d , said substation apparatus extending by line conductors 13 and 14 from the substation to an exchange.

- 5 Assume now that the subscriber at A^1 desires to make a call and to obtain connection with the subscriber's set whose substation apparatus is shown at B^1 , he will take his receiver from the hook closing the contacts 15 thereof and completing a circuit including the contacts 15, the dial interrupter d , line conductors 13 and 14, circuit conductors 16 and 17 thru normal contacts 18 and 19 of the relay 20, circuit conductors 21 and 22, the 10 normal contacts 23 and 24 of the relay 25 to the ground pole at 26, and to the negative pole at 27 of the central station source of current 28, thru the line magnet 29, the said magnet and the said source of current being 15 shown on an extension of the conductor 30 leading from the contacts 24 of the relay 25, the said extended conductor being shown in Fig. 2, leading to the relay 29 which is a high resistance relay, and to multiple contacts 31, 32 and 33 of the connection switch whose circuits are illustrated in Fig. 2, and which connection switch is of the cross-bar type similar to that described in my patent 20 above referred to.
- 20 The relay 29 in this connection switch is used as a line bar magnet to displace a line bar associated with the calling line located on the said connection switch to condition the contacts 31, 32, or 33 to make connection 25 with the co-operating contacts 34, 35, or 36, depending upon which trunk A^2 , B^2 or C^2 with which the said pairs of contacts are respectively associated, is capable of being seized for use by the calling line as will be 30 now explained.

The line relay magnet 29 having operated, it will close its contacts 37, completing a circuit traced as follows: from the ground pole of the source of current, the contacts 37 of the relay 29, circuit conductor 38, and assuming that the first trunk which is C^2 is not at the time in use and therefore selectable, the circuit will be continued thru the contacts 39 of the relay 40, the winding of the vertical magnet VM of the connection switch to the negative pole of the source of current 28, the vertical magnet corresponding to the trunk circuit C^2 and the vertical bar V being thereby displaced and latched in its displaced condition by the co-operating latch members 41.

The line bar under the control of the magnet 29 having been operated, and the trunk bar V having now been operated, the switch contacts 33-36 and 42-43 will now be closed by the conjoint action of the said bars; the manner in which this is done will be apparent from the description of the operation of the connection switch described in my patent referred to above, and will be ex-

plained however, later in connection with the disclosure of Fig. 5, showing parts of such a connection switch with slight modifications.

Suffice it to state however, for the time being, the switch contacts 42-43 and 33-36 will remain closed for the entire connection regardless of the condition of the energization of the magnet 29, and the said contacts can only be restored to their normal opened position by the operation of the restoring magnet RM, also the trunk bar can only be restored to normal by the operation of the release electromagnet N; these last-named magnets being inoperative for the time being.

By the operation of the connection switch contacts just described, a pair of conductors including the conductor 30 in circuit with the subscriber's telephone and the conductor 44 leading to the winding of the magnet relay 25 shown in Fig. 1 associated with the line circuit and connection switch of Fig. 1 are extended thru the said contacts to circuit connection with the conductors 45 and 46, respectively.

The conductors 45 and 46, as well as the conductor 47 leading to the restoring magnet RM of the switch and release magnet N thereof, and the conductor 48 leading to the magnet 40 for a purpose to be later described are shown extended in the disclosure of Fig. 4 to like referenced conductors 45, 46, 47 and 48 in Fig. 4 at the bottom of the sheet.

Referring now to the switch structure illustrated in Figs. 5, 6, 7 and 8, a brief description thereof will now be had to better understand the disclosures of Figs. 1 and 2 involving the use of such switch structure.

Fig. 5 shows portions of the switch structure in side elevation, portions of the supporting frame being omitted for the sake of clearness.

In Figs. 5 and 7, at O, I show an operated plug carriage. This plug carriage consists in brief of a metal frame FR having slots at W and R, the said slots being for the purpose of admitting the key-pin K of a line bar H, whereby the said key-pin shown in Fig. 7 in the unlocked position of the plug carriage may lock and unlock the plug carriage. Also the slot R admits the vertical bar V carrying a key member F, which member is also shown in its unlocked position in Fig. 7, but which may in the locked position of the plug carriage O enter the opening R thereof to lock the same in normal position. Such a locked plug carriage is shown at L in Fig. 5 and Fig. 6, the key-pin K being shown in its plug carriage locking position, and the key member F also being shown in its plug carriage locking position in Fig. 6.

Propelling springs s shown in Fig. 5, propel the plug carriages to the position of the plug carriage O in Figs. 5 and 7 whenever the said plug carriage is operatively unlocked by the conjoint unlocking action of

the two key members F and K, belonging to a trunk bar V and a line bar H, respectively.

When thus unlocked the metallic plugs 8, 9 and 10 will be carried to contact operating position wherein the pairs of springs 2—3, 4—5, 6—7, are interconnected for circuit operative purposes. When so operated the plug carriage, such as O, can thereafter be restored to normal position by the operation of a restoring magnet RM shown in Figs. 5 to 8 inclusive, which restoring magnet being energized by suitable circuit connections will attract its armature Y, thus causing the restoring member M to force a previously operated plug carriage, such as O, back to normal position by the cam surface e engaging the cam pin C carried on the plug carriage. The plug carriage being restored to normal position, the key-pin K which is yieldingly carried on the line bar H for the plug carriage O, will take the position of the key-pin K of Fig. 6 for the plug carriage L which is a restored plug carriage.

To unlock such a plug carriage as is shown in Figs. 5 and 6, at L, the line magnets as LM are energized and move the key-pin K from its normal position as shown in Fig. 6, to the position of K₀ shown in Fig. 6 in dotted lines. Also the vertical magnet V will be displaced from its position of rest wherein the key member F of Figs. 5 and 6 rests in such a horizontal plane that it will obstruct the movement of the plug carriage, and will take the position shown in Fig. 5 wherein the key member F is moved without the opening F and below the horizontal plane of the plug carriage frame, and the conjoint removal of the key members F and K from their normal positions will allow the plug carriage to be propelled under the power of the spring s to its operated position shown for the plug carriage O in Figs. 5 and 7.

Any other plug carriage, such as the plug carriage OO, may be also operated simultaneously with the operation of the plug carriage O, if its line bar HH is displaced by its own line magnet LM, at the same time as the line bar of the plug carriage O, and before the displacing of the vertical bar V by the energization of the vertical magnet VM.

I have described how the plug carriages are restored to normal position by the energization of the restoring magnet RM, and in addition to the restoring function of the magnet RM a restoring function is also performed by the electromagnet N when energized, in that it will attract the armature latch member l and withdraw it from its trunk bar latching position to a position wherein the trunk bar will be restored to normal position by the compression spring J propelling the said vertical bar upward.

Contact springs 252 and 184 are provided to control suitable circuits such as are described elsewhere in this specification.

Figs. 5 and 8 show an unoperated plug carriage Z which is locked from operation by the prior operation of the plug carriages O and OO in the same vertical row and controlled by the same vertical trunk bar V. This locking is accomplished as will be seen by reference made to the Figs. 5 and 8, by the pin P carried by the member M entering slot S of the plug carriage. This locking by the members M associated with all of the unoperated plug carriages in the same vertical row of the connection switch as an operated plug carriage is effective until the final restoration of the operated plug carriages upon the energization of the electro-magnet RM associated therewith, at which time by the removal of the pin P from the slot S, the plug carriages are again made available for use.

The disclosure of Fig. 4 and the disclosure of Fig. 3, are associated only with a particular trunk line as C², it being understood that the other trunk lines, such as A² and B², are equipped in a like manner as the trunk line C² with like controlling magnets, apparatus and circuit conductors as is illustrated in Figs. 2, 3 and 4 for the trunk circuit C²; the arrangement being such that if one trunk circuit as C² is busy, a second line making a call will be connected to the next succeeding trunk circuit as B², etc.

Continuing the narrative of operation, the operation of the connection switch of Fig. 2 having extended the calling line circuit to the conductor 45, the impulse relay IMP will be thereupon operated, being connected in multiple with the high resistance line magnet relay 29 of Fig. 2, and the relay IMP being of relatively low resistance practically all of the line current will traverse the winding of the said relay; this shunting of the high resistance magnet 29 will be ineffective to restore the connection switch contacts 33—36 and 42—43, even though such magnet 29 is sufficiently deenergized by such shunting to restore its contacts and its associated line bars to their normal positions, since at this time the control over the said switch contacts is exercised by the apparatus individual to the trunk circuit C².

The trunk circuit C² having been thus selected, the apparatus of Figs. 3 and 4 which are individual to the trunk circuit C² are now available to the use of the calling subscriber to facilitate under the subscriber's control the setting-up of the connection to the called subscriber's line including the automatic selection of the said line, and the automatic selection of a separate interconnecting link circuit by which the calling and called lines are united for conversational purposes.

The impulse relay IMP will be operated as before described almost instantly after the subscriber takes his receiver from the hook. It operates its contacts closing three pairs of contacts and opening one pair of contacts. The contacts 77 now being closed, the relay 78 which is of the slow releasing type will attract its armature breaking the contacts 49 in the circuit of the winding 50 of the relay 51.

At this time it may be stated that the relay 78 will remain energized when the contacts 77 in its energizing circuit are vibrated, and will keep the contacts 49 in the operating circuit of the relay 51 open until a definite period of time after the circuit of the impulse relay IMP has been broken; which condition occurs only when the dialling or setting-up circuits of Figs. 3 and 4 have completed their functions, and the subscribers are in conversational circuit one with the other, or if the calling subscriber should replace his receiver upon the hook before the completion of the dialling operation, in which case the contacts 49 being closed a circuit will be completed for the energizing winding 50 of the relay 51 including the source of current 28 and the contacts 52 of the relay 53 which will be closed by the operation of the relay 53 as will be later described.

The breaking down of the connection due to the subscriber hanging up his receiver prior to completing the dialling function will not now be described in detail, as it will be understood how this can be done by the operated relay 51 which is the relay controlling the breaking down of the connection of the dialling circuit and the calling line; and the method in which this relay is employed to break down an established connection will be described in detail in this narrative, since the same thing occurs in the same way when the subscriber has completed the dialling function and has been connected to the called subscriber's line by the connection switch shown in Fig. 1.

The operation of the relay 78 also closes contacts 65 in the circuit of the relay 40 shown on Fig. 2, the circuit being traced as follows: from the negative pole of the source of current thru the winding of the relay 40, circuit conductor 48 which is shown extended on Fig. 4, the contacts 65 of the relay 78 to the ground pole of the source of current.

The contacts 65 after the dialling operation has commenced are shunted by the contacts 64 of the relay 53 which is thereupon operated as will be later described, and these two pairs of contacts maintain the operative circuit of the relay 40 which is now operated until the dialling circuit reverts to common use as will be later described.

The relay 40 being operated the circuit conductor 38 is extended by the contacts 66 thereof to the circuit conductor 67, the contacts 68 of the like relay 40 of the next succeeding trunk or stepping-up circuit B², and from thence by means of the circuit conductor 69 to the vertical magnet of the trunk circuit B² not shown in the drawing. It is by this means that the selecting circuit comprising in part the conductor 38 which selected the trunk or setting-up circuit to be used in establishing a connection, is extended from the busy trunk to the next succeeding idle trunk.

The impulse relay IMP also closes its contacts 54 in the circuit of the motor magnet MM of the rotary selector switch RS of Fig. 3, the circuit for the said motor magnet MM being traced from the negative pole of battery through the winding of said magnet, circuit conductor 55 which is continued on Fig. 4, and leads thru the contacts 54 of the relay IMP to the ground pole of battery. The motor magnet thereupon attracts its armature lifting the pawl attached thereto from one notch of the notched wheel WH to the next succeeding notch to the left thereof. At the same time the spring SP is extended and tends to restore the armature to its normal position against the power of the magnet MM, and to cause the pawl to propel the notched wheel WH on the shaft 56, a portion of the revolution corresponding to the angular distance between the notches on the said wheel. But for the time being the wheel remains in its normal position as does the shaft 56, and the carried switch arms 57 and 58.

The switch arm 57 in its normal position rests on an idle contact to which no conductor is attached, and is therefore impotent to control an electrical circuit in this position.

The switch arm 58 however rests upon the normal contact NOR, and thereby connects its connected ground conductor to the circuit conductor 59 which is extended from Fig. 3 to Fig. 4; and the connection to ground comprising this conductor 59 and the switch arm 58 for the time being produced a short circuit about the winding of the relay 53, so it cannot be operated even though the contacts 60 of the slow releasing relay 78 are closed as is now the case by the closure of the contacts 77 of the impulse relay IMP as just described.

The calling subscriber may now operate the dial *d* at his telephone instrument A¹, causing the circuit of the impulse relay IMP which has been described to be interrupted a number of times, the number of interruptions corresponding to the numeral of the first digit of the called subscriber's line number.

We will assume in this description that

the called subscriber's line number is No. 32. The first numeral indicating the 10's digit of the line number being 3, the number of interruptions caused to be produced by the 5 dial of the calling subscriber will likewise be 3. The impulse relay IMP will thereupon be rapidly vibrated three times from its operated position at the end of which period it will again come to its fully operated 10 position. During these interruptions and consequent vibrations of the impulse relay contacts, certain circuit changes are effected as follows:

At the instant of the first break in the line 15 circuit the impulse relay breaking its contacts 54, 61 and 77, the motor magnet MM in circuit of the contacts 54 will be momentarily restored to its normal position causing the pawl attached to its armature to propel 20 the notched wheel WH one notch, and thereby to rotate the shaft 56 thereof which carries the switch arms 57 and 58 one step. The switch arm 58 thereupon moves the normal contact NOR to the off-normal contact ON of the said switch, producing circuit 25 changes as follows:

The relay 78 will not be responsive to the rapid interruptions of the contacts 77 which will retain its armatures in their attracted 30 position, this being the property of such a slow releasing relay. The contacts 60 thereof will remain closed, and since the contacts 58-NOR are now opened the short circuit previously described as being placed about 35 the winding 53 will be removed, and the relay 53 will be energized over a circuit traced as follows: from the ground pole of battery, the winding of the relay 53, the contacts 60 of the relay 78, the resistance 62, 40 to the negative pole of battery. The flow of current over this circuit will operate the relay 53, causing it to close its contacts; the contacts 52 being closed to condition the relay 51 for subsequent operation as will be 45 later described. The contacts 63 form a locking circuit for the relay 53 to maintain its operated condition in circuit with the resistance 62 and the source of current; the contacts 64 being closed to shunt the contacts 65 in the circuit of the relay 40 to insure its continued operation during the complete connection setting-up period.

The switch arm 58 as has been stated now 50 contacting with the off-normal contact ON of the switch, completes a circuit from the ground pole of battery thru the said switch arm and the said switch contact, and circuit conductor 70 which is extended on Fig. 4 to the winding of the off-normal relay ONR, 55 and from thence to the negative pole of the source of current. The circuit for the said source being completed thru the relay winding, this relay will be operated closing three pairs of contacts 71, 72 and 73, completing 60 circuits to be described.

The circuit of the interval relay INT will now be closed, the same being traced from the ground pole of battery thru the winding of the said relay, contacts 73 of the relay ONR thru the winding of the relay IR to 70 the negative pole of the source of current, which flowing over the circuit just traced causes the interval relay INT to be operated closing the contacts 74 and opening the two pairs of contacts 75 and 76 for purposes later to be described. 75

The relay IR will also be operated by the said flow of current and will close its contacts 79 for a purpose later to be described.

The interval relay INT will be intermittently short circuited by the successive operations of the impulse relay IMP under the control of the calling subscriber's dial, but its adjustment and electromagnetic characteristics will be such that it will maintain its 80 operative condition until it is short circuited by the contacts 61 of the relay IMP for a definite length of time which is longer than the interval intervening between successive 85 interruptions of a chain of interruptions 90 produced by a calling subscriber's line. But as will be later related, between each chain of interruptions produced by the calling subscriber's dial the contacts 61 will be closed long enough to cause a short circuit of 95 the relay INT of sufficient duration to insure its restoring to its normal inoperative condition.

The switch arm 57 will be stepped from one contact to another of the row of contacts 100 with which it is associated in unison with the interruptions of the calling subscriber's dial under the propelling action of the spring SP of the selector switch. The circuit of the conductor 80 connected to the switch arm 105 57, and which conductor 80 is shown extended from Fig. 3 to Fig. 4, leads in Fig. 4 to the break contacts 76 of the relay INT which are maintained open during the operation of the calling subscriber's dial, the circuit being previously continued thru the said 110 contacts 76 to the normally opened contacts 79 of the relay IR over a circuit including circuit conductor 81, the normal contacts 82 of the relay NB, the circuit conductor 83, 115 normal contacts 84 of the relay PD, circuit conductor 85 to the said contacts 79 of the relay IR.

The closure of the contacts 79 has been 120 previously mentioned, but the circuit controlled thereby from the grounded pole of battery at 86 to the switch arm 57, is broken at the contact 76 of the relay INT prior to the closure of the contacts 79 of the relay IR. This insures that the switch arm 57 is 125 not operatively connected to the ground pole of battery 86, and is therefore unable to produce any electrical effect upon the circuits connected to the row of contacts 87, 88, etc., 130 over which it may pass, preceding and dur-

ing the first series of impulses. The contacts 71 and 72 of the relay ONR are also inoperative during this period to produce any electrical effect by their closure, since the conductors leading therefrom lead only to contacts open circuited at this stage of the operation of the system.

At the end of the chain of interruptions caused by the first operation of the subscriber's dial other circuit changes will be effected.

Assuming that the called-for subscriber's number is as has been stated No. 32, the first chain of interruptions thereby being three in number, the selector switch arm 57 will be moved successively over the contacts 87 and 88 of the selector switch finally coming to rest on the contact 89 thereof. The impulse relay now holds its contacts 54, 61 and 77 securely closed for a sufficient length of time to cause the release of the interval relay INT by its being short circuited by the contacts 61 of the relay IMP, whereupon the following circuit changes are effected.

The circuit leading from the ground pole of battery thru the contacts 79 of the relay IR will now be completed over the circuit conductor 85, the normally closed contacts 84 of the relay PD, the circuit conductor 82, normal contacts 83 of the relay NB, circuit conductor 81, the now and normally closed contacts 76 of the relay INT, circuit conductor 80 which is extended on Fig. 3 to connect with the switch arm 57 and which at the time contacts with the contact 89 of the switch; the circuit being continued thru the said switch arm and said contact over circuit conductor 91, circuit conductor 92, the normally closed contacts 93 of the relay BR, circuit conductor 94 which being extended on Fig. 4 leads thru the winding of the digital relay DR³ to the negative pole of the source of current. This will cause the operation of the digital relay which will close its contacts 95 and 96. The contacts 95 being closed, condition for operation the relay BR of Fig. 3 over circuit conductors 97, also 98 and 592 on both Figs. 4 and 3, the conductor 98 leading from the said relay BR thru now closed contacts 72 of the off-normal relay ONR to the ground pole of battery.

The circuit just traced from the contacts 95 to the ground pole of battery including the said contacts, will be impotent however to operate the relay BR in series with the relay DR³ and the source of current connected to the terminals of the said relay, because the said relay BR is at the time short circuited by the connection to ground over the circuit conductor 94 of both Figs. 4 and 3, the contacts 93 of the relay BR, the switch contacts 57 and 89 of the selector switch, the conductor 80 of both Figs. 3 and 4, and the other conductors and contacts leading therefrom to the ground pole of battery includ-

ing the contacts 76 of the relay INT, the contacts 82 of the relay NB, the contacts 84 of the relay PD, and the contacts 79 of the relay IR.

The subscriber now having caused the first chain of interruptions vibrating the impulse relay IMP, now again operates his interrupter to send the second chain of interruptions, which under the assumption that the called-for subscriber's number is No. 32, consists of two interruptions of current in the circuit of the impulse relay IMP. At the moment of the first interruption of current by the second actuation of the subscriber's dial, spring SP of the motor magnet MM will cause the switch arm 57 to advance breaking its connection with the contact 89 in the circuit of the relay DR³ of Fig. 4, and thus removing the short circuit which has been existing about the winding of the relay BR. The relay BR will now operate being placed in a locking circuit serially connected with the winding of the relay DR³ and the source of current, the said circuit including the contacts 95 of the relay DR³ and the contacts 72 of the relay ONR. The relay BR having operated, its contacts 99 will now be closed completing a circuit including the source of current and the winding of the relay PD on Fig 4, the said circuit including circuit conductor 100 of Figs. 3 and 4.

The relay PD now being operated will attract its armatures breaking the contacts 84 thereof which have previously been described as being in the circuit of the switch arm 57 of Fig. 3, and the contacts 101 being closed the winding of the busy test relay BT will be conditioned to be placed in operative relation to the said switch arm 57.

As soon as the second chain of interruptions have ended, the contacts 76 of the interval relay INT will again be closed in the same manner as has been described at the end of the first chain of interruptions; these contacts 76 opening during any operation of the dial by the subscriber. During the dial operation the contacts 74 of the interval relay will be closed, and the contacts 102 of the relay PD now also being closed, the slow releasing relay 103 will be operated during the said second dial operation slowly being restored to normal thereafter when the contacts 74 of the interval relay are again opened upon the interval relay being restored to normal. The contacts 104 of the relay 103 will therefore be opened and after a given interval following the dial operation will again be closed. During this interval the busy test function takes place as will later be described. Before considering the busy test function the operation of other apparatus will be considered.

The relay DR³ and PD of Fig. 4 having been operated, a circuit will be completed

including the contacts 105 of the relay PD and the contacts 96 of the relay DR³ comprising the source of current and the winding of the relay DL³, which relay will be operated thru the said closed pairs of contacts. This relay being operated will connect to the contacts of the switch RS immediately following the first selected contact 89. The called-for line magnets of a group of ten lines controlled by the relay DL³, will be connected to the next contact of the switch RS succeeding the first selected contact 89. These next ten contacts are designated 106, 107, 108, 109, 110, 111, 112, 113 and 114 and are thereby associated in the use of the switch here described with the line magnets of the group of ten lines numbered 31 to 40.

It will be obvious from what has been said, the switch arm 57 need only advance one step from its first selective position to be connected with a circuit conductor associated with a line magnet of line 31, and two steps for the line magnet of line 32, and so on. In the case here considered it being the line 32 which is being selected, the switch arm 57 will come finally to rest on the contact 106.

It has not yet been stated, but it is the case that when the relay BR was operated all of the contacts, such as the contacts 93 and the other nineteen like contacts associated therewith are broken so that the switch contacts 87, 88, 89, 90, 106, 107, etc., herein illustrated as being twenty in number are electrically disconnected from their associated relay magnets, such as the relay magnets DR¹, DR² and DR³ shown on Fig. 4, which as shown in the drawing are connected to the contacts 87, 88, 89 and 90 of the switch RS, by circuit conductors leading thru break contacts of the relay BR 115, 116, 93 and 117. These contacts being broken the connection between the contacts of the switch RS and the digital controlling relays DR¹, DR², DR³, DR⁴, etc. will be severed. The relay DR³ however will be maintained operative by the locking circuit before described including the winding of the relay BR.

It is to be noted that each of the relays DR¹, DR², DR³, DR⁴ and others not shown, are like relays performing like functions, and control like digital relays DL¹, DL², DL³ and DL⁴. These last-named digital relays when operated by the switch arm 57 under the control of the subscriber's dial by having come to rest upon the proper contact of the switch RS, serve to thereafter connect to the next succeeding contacts of the switch RS in numerical order the line magnets of the group of lines under the control of the particular digital relay first selected. In this way I am enabled by simply

continuing the motion of the switch arm 57 of the switch RS under the control of the subscriber's dial, to cause the said switch arm to pass over the line magnets of the particular group of lines selected in turn until the particular magnet of the called-for line 70 may be selected and placed in operative circuit relation with the switch arm 57, as will be described in detail for the line magnet of the line 32.

Assuming now that the subscriber as has been described, causes the second actuation of his dial to propel the switch arm 57 to its second position of rest on contact 106, a circuit will be thereby completed including the switch arm and contact 106, said circuit being traced as follows: from the negative pole of the source of current thru the winding of the busy test relay BT shown on Fig. 4, contacts 101 of the relay PD which are now closed, normal contacts 82 of the relay NB, normal contacts 76 of the relay INT, circuit conductor 80 which being extended on Fig. 3 leads to the switch arm 57 of the switch RS, the contact 106, circuit conductor 118, circuit conductor 119, the now closed contacts 120 of the digital relay DL³, circuit conductor 121 which being extended on Fig. 4 leads therefrom to the connector switch of Fig. 1 and is connected to one side of the winding of the line magnet 122, the other side of the said winding being connected to the negative pole of battery. This circuit being completed there will be no flow of current over the same if the called-for line is not busy.

In the consideration of the busy test function at this time it is necessary to state that when a line, such as that leading from the substation A¹ or the substation B¹ and terminating in the line apparatus of Fig. 1 is busy, one of the line magnets serving as cut-off relays for the lines of which there are a pair for each of the lines will be energized. The particular magnet energized depends as will be later more clearly seen upon whether the line is a calling or called line. In the embodiment illustrated we are describing the line from substation A¹ as a calling line, and the line leading to substation B¹ as a called line.

Since each of these line magnets have one of their winding terminals permanently connected to the negative pole of battery, the energization of such a magnet is and can only be caused by a connection leading from the opposite or ground pole of battery to the other winding terminal. It is the presence of a ground connection on the circuit side of these line magnets that operates to produce a busy characteristic to the line to prevent it from being connected to by a calling line. For the present in this description we will assume that the called line 32 which is the

line leading to the substation B¹ is not busy; the operation of the circuits involved thereupon being as follows.

The contact 104 having been momentarily opened and again closed as has been described to produce the busy test interval, a circuit will be completed for the "not busy relay" NB to operate the same, the circuit being traced as follows: from the negative pole of battery, the winding of the relay NB, contacts 131 of the relay BT, the contacts 104 of the relay 103, the normal contacts 75 of the interval relay INT, the now closed contacts 102 of the relay PD, and therefrom to the ground pole of battery. This circuit being closed a locking circuit for the "not busy" relay NB is therefore traced as follows: from the negative pole of battery thru the winding of the relay NB, thru the contacts 132 of the said relay, the contacts 71 of the relay ONR which is the off-normal relay, to the ground pole of the source of current. This circuit operatively locks the relay NB for the remainder of the connection setting-up period. The apparatus is now in condition to be operated, to perform the final act to initiate the connection by interconnecting switch contacts of both of the lines on the switch of Fig. 1 by means of an interposed link circuit which we will assume in this description is the link circuit LK. The link circuit in this description is assumed to be the first link circuit in order, that is, not at the time in use. Although there are a plurality of setting-up circuits such as illustrated in Fig. 3 and Fig. 4 and in part in Fig. 2, there are two sets of mechanisms FLC in Fig. 1, and at BTD in Fig 1, which are common to all of the setting-up circuits and mechanisms being used by any of them; the apparatus at FLC being capable of use by one setting-up mechanism at a time, and when taken for use by a setting-up mechanism effectively prevents another-setting-up mechanism which may be immediately thereafter prepared to perform the final connection function from so doing until after the said function has been performed by a setting-up mechanism which has previously taken the apparatus of FLC for use to perform this final setting-up function.

The method by which this is accomplished will now be apparent from the following description of its operation in connection with the continued operation of the apparatus involved in completing the connection which is being described:

The relay NB being operated will if the common apparatus FLC is not at the time in use, complete a circuit for the winding of the relay SIR, the said circuit being traced as follows: from the ground pole of the source of current thru the contacts 133 of the relay NB, the winding of the relay SIR, conductor 229, the normally closed contacts

134 of the relay FLC of the common apparatus FLC, thru the protective resistance coil 135 to the negative pole of the source of current. This will cause a flow of current over the circuit just described, operating the relay SIR. The operation of this relay which may be called the selective interlocking relay determines the moment when the setting-up mechanism associated therewith is to perform its final function or setting up function of the switch of Fig. 1.

The relay SIR being operated will operate its contacts 136, 137, 138 and 139 to perform functions later to be described. The contacts 137 are closed to complete a circuit to operate the line magnets of the calling and called lines in parallel, the circuit of each being separately traced as follows; it being understood that the operation of both proceeds simultaneously.

The circuit of the line magnet which is the line magnet 122 of the called-for line which leads to the substation B¹ is traced as follows: from the ground pole of the source of current, the now closed contacts 137 of the relay SIR, the normally closed contacts 140 of the relay RIS, the now closed contacts 141 of the relay NB, circuit conductor 81, now closed contacts 76 of the interval relay INT, the circuit conductor 80 which being extended from Fig. 4 to Fig. 3 leads in Fig. 3 to the switch arm 57 of the switch SR, the now closed contacts 57, 106 of the said switch circuit, conductor 118, circuit conductor 119, the now closed contacts 120 of the relay DL³, circuit conductor 121 which upon being extended to Fig. 4 leads across the said figure, and is thereafter extended to circuit conductor 121 of Fig. 1, the contacts 142 of the relay 123, and from thence thru the winding of the relay 122 to the negative pole of the source of current. The relay 122 will thereupon be operated and open its contacts which extend back to the calling conductors leading to dialling or setting-up selective mechanisms on Fig. 2. The relay magnet 122 being operated will also operate the called line bar of the line with which it is associated and which is assumed to be line No. 32 in this description, thereby conditioning for operation the sets of contacts 143, 144 and other sets of contacts associated with the line not shown in Fig. 1, but which may be provided in accordance with the traffic requirements of the system and which depend upon the number of link circuits required to handle the said traffic.

Each of the said sets of contacts are associated with a like co-operating set of contacts belonging to a link circuit for interconnecting telephone lines, such as the link circuit LK and the link circuit LK² in Fig. 1.

In the meantime the contacts 139 of the relay SIR having been closed, a circuit is completed including the winding of the re-

lay XR, thru the contacts 150 and includes the contacts 139 and the source of current. Current from the said source will operate the relay XR which will attract its armature 5 closing contacts 151, and opening contacts 152 in the circuit of the impulse relay IMP. The relay IMP is thereafter continued in its operated condition thru the contacts 151 of the relay XR, the contacts 150 of the relay 10 RIS and the contacts 189 of the relay SIR thru which contacts a connection to the ground pole of battery is maintained for the relay IMP.

The relay 153 is connected to the conductor 48 thru contacts 154 and is operated over the same circuit including the conductor 45, leading back over the line of the calling subscriber thru contacts 24 of the subscriber's cut-off relay 25 which is shown in Fig. 1, and 15 which circuit has been previously described as the operating circuit of the impulse relay IMP; the relay 153 being substituted in the circuit at this time for the relay IMP.

Subsequent to the closure of the contacts 154 of the relay XR and momentarily subsequent to the opening of the contacts 155 of the relay 153, the contacts 156 of the relay XR will be closed. The sequence of contact operation being provided by the construction and adjustment of the relay.

The contacts 157 in the circuit of the calling line cut-off relay magnet will now be closed.

The circuit of the calling line relay magnet will now be traced as follows: from the grounded pole of the source of current, the contacts 137 of the relay SIR, the now closed contacts 140 of the relay RIS, the contacts 145 of the relay NB, the contacts 157 of the relay XR, circuit conductor 46 which extends from Fig. 4 to Fig. 2, and on Fig. 2 leads to the now closed contacts 42 and 43 of the connection switch of Fig. 2, circuit conductor 44 which is extended from Fig. 2 to Fig. 1, and which on Fig. 1 leads thru the winding of the calling line magnet 25 to the negative pole of the source of current. Current flowing over this circuit will operate the line relay magnet 25 which will sever at 45 the contacts 146 the circuit of the conductor 147 leading to the called line magnet 20 of the calling line, and the contacts 148 being closed will connect a busy ground potential upon the conductor 147 leading to the dialling or setting-up circuits so that the line will test busy to calling lines calling the number of the present calling line.

The contacts 24 and 23 in the circuit of the subscriber's station and leading by means of the conductor 30 and other interposed contacts and conductors previously described to the conductor 45 of Fig. 4 will now be opened. This will cause the release of the relay 153 in Fig. 4 connected to the 60 conductor 45.

The release of the relay 153 is an indication that the line magnets have been properly operated to condition the connection of the interconnecting circuit to the lines, and the contacts 155 of the relay 153 now restored 70 to their normal closed condition, a circuit is completed for relay RX, the circuit being traced as follows: from the grounded pole of the source of current, contacts 155 of the relay 153, the now closed contacts 156 of the 75 relay XR, the winding of the relay RX to the negative pole of battery.

The relay RX will now be operated, and I preferably make this relay a slow operating relay and preferably of the type indicated in the drawing, though any other type of slow operating relay may be used.

The relay RX being operated will after an interval close its contacts 158, thereby closing a circuit comprising the following: the central source of battery the winding of the relay FLC shown on Fig. 1, which relay is common to a plurality of setting-up circuits, the circuit conductor 159 which is shown extended to conductor 228 in Fig. 4, the winding 166 of the relay SIR, armature and contact 136 of this relay, armature 160 and back contact of relay RIS, contacts 158 and relay RX, circuit conductor 161, which is shown extended in Fig. 1 thru the normal contacts 162 of the relay 163 of Fig. 1, and the winding of the slow releasing relay 164 and the winding of the vertical magnet 165 of the connection switch shown in Fig. 1 associated with the link circuit LK.

In this description it is assumed that the link circuit LK is the first idle link circuit, and the operation thereof is described accordingly; it being understood that as will be later described the circuit conductor 161 105 would be extended by means later to be described to the next succeeding link circuit LK² to select the same for use if the link circuit LK were at the time in use.

This circuit just described being completed including the source of current, current from the said source will operate the slow releasing relay 164 and the common controlling relay FLC both of which are shown in Fig. 1. The common controlling relay FLC being operated will prevent any control over the connection switch of Fig. 1, or any part thereof to be exercised by any other dialling circuit for a given period wherein the dialling or setting-up circuit whose operation has been described itself controls the 110 operation of the apparatus of said switch.

The breaking of the contacts 134 thus disabling the relay SIR of another dialling or setting-up circuit is the means employed to 125 prevent the said control being exercised by another dialling or setting-up circuit during the operation of the relay FLC. The relay SIR of the described dialling or setting-up circuit is maintained operated how- 130

ever by the winding 166 thereof, being included in the circuit just described and which winding maintains the energization of the electro-magnet of the relay SIR.

- 6 The relay 164 being operated closes contacts 167 which are placed in multiple with the contacts 162 of the relay 163 to maintain the circuit of the relay 164, the magnet 165, the relay FLC, and the relay SIR independent of the contacts 162 after the relay 164 is operated, and until the contacts 167 themselves shall as will be later described, be broken. The contacts 168 of the relay 164 are now broken, and as they are included in the initial operating circuit of the next succeeding link circuit LK², the breaking of these contacts prevented for the time being, the next succeeding link circuit from being operated.
- 10 The vertical magnet 165 having operated it will attract the vertical bar 169 of the connection switch, which vertical bar is associated with the link circuit LK, and the operation of this vertical bar will cause the interconnection of the link circuit, contacts 170, 171 and 172 of the said connection switch to the associated co-operating contacts 173, 174 and 175, respectively. Also the operation of the trunk bar 169 of the link circuit LK will cause the contacts 176, 177 and 178 associated with the said link circuit to be connected to the contacts 179, 180 and 181 co-operating and associated with the said link contacts.
- 15 The interconnecting of both ends of the link circuit with the two lines by the two sets of co-operating contacts accomplishes the interconnection of the said lines subject to the control of the apparatus in the said link circuit LK.
- 20 The description of the connection switch of Figs. 5, 6, 7 and 8 will not here be repeated in detail, as it has been previously described and its operation will be understood.
- 25 The connection switch contacts 170—173 and 172—175 shown on Fig. 1 having been closed, a circuit is completed for the calling subscriber's battery feed relay 188 of the link circuit including the tandem windings of the relay 188 in series with the source of current, the same being connected thru the said switch contacts to the limbs of the telephone lines 13 and 14 leading to the substation telephone apparatus at A¹. The relay 188 will thereupon attract its armatures, closing the contacts 187, 199 and 202, and opening the contacts 203.
- 30 The trunk bar 169 having accomplished the interconnection of the lines is latched in its operated position by co-operating latch members 182. This latch is subject to the control of an electro-magnet 183, which however for the time being is inoperative to release the trunk bar 169.
- 35 The contacts 171—174 of the connection

switch now being closed, a holding energizing circuit for the line magnet relay 25 of the calling line will be completed including the said contacts traced as follows: from the ground pole of battery, the windings 186 of the relay 163, the contacts 187 of the relay 188, the circuit conductor 189, now closed contacts 171—174 of the connection switch, circuit conductor 190 leading to one side of the winding of the relay 25, the other side of the winding being connected to the negative pole of the source of current. In this way the winding 186 of the relay 163 is placed in series with the winding of the relay 25, and the source of current. But this winding being at the time short circuited by the conductor 44 of Fig. 1, leading thru the connection switch contacts of Fig. 2 and continued as conductor 46 to Fig. 4, leads on Fig. 4 to the ground pole of battery thru the contacts 157 of the relay XR, contacts 145 of the relay NB, contacts 140 of the relay RIS, and contacts 137 of the relay SIR. Thus until the circuit of the conductor 44 just described is broken, the relay 163 will not be operative.

The pair of connection switch contacts 177—180 shown on Fig. 1 having been closed as before described, a holding circuit is completed for the called line relay magnet 122 traced as follows: from the negative pole of the source of current, the winding of the magnet 122, the contacts 177—180 of the connection switch which are now closed, circuit conductor 201 leading thru the winding of the relay 204, to the ground pole of battery. Thus in addition to establishing a holding circuit for the relay magnet 20 controlling the line bar of the called line, a circuit is completed for the winding of the relay 204 of the link circuit which causes the operation of the said relay 204 to close its contacts 205 for a purpose to be later described.

The relay 204, at this time being placed in multiple with the resistance coil 185 thru which resistance coil the operative circuit of the magnet 122 had been completed, this previously completed circuit as before described comprises the contacts 146 of the relay 25 shown in Fig. 1, the conductor 121 leading therefrom, and which being extended on Fig. 4 led thru contacts 120 of the relay DL³ thru co-operating switch contacts of the stepping switch RS and circuit conductor 80 leading thru contacts 76 of the relay INT of Fig. 4, also thru contacts 141 of the relay NB, and resistance coil 185 to the ground pole of battery thru contacts 140 of the relay RIS and contacts 137 of the relay SIR.

The relays 188 and 204 have been operated and a circuit is completed to initiate the discharge of the setting-up dialling circuits of Figs. 2, 3 and 4, so that it can revert to common use; the primary circuit to cause

the said discharge is traced as follows: from the ground pole of battery, thru contacts 205 of the relay 204, contacts 202 of the relay 188, normal contacts 206 of the relay 163, 5 circuit conductor 207 which is at this time extended to the dialling circuit of Fig. 4 by conductor 207 of Fig. 4, and leads therefrom thru now closed contacts 138 of the relay SIR and the winding 208 of the relay 10 RIS to the negative pole of the source of current. Current from the said source flowing over the traced circuit causes the operation of the relay RIS attracting its armatures and breaking its contacts 140, 150 and 15 160, and closing contacts 209 all for purposes to be described.

The contacts 209 being closed complete a locking circuit from the ground pole of battery to the negative pole thereof, thru the 20 winding 210 of the relay RIS, the contacts 209 thereof, and now made contacts 211 of the relay NB. This locking circuit maintains the operation of the relay RIS independent of the contacts 138 just mentioned.

25 The contacts 140 being broken in the common circuit of the originating circuits leading to the two line magnets of the two connected lines, the shunting effect of the ground connected to the contacts 140 by the 30 relay SIR will be eliminated and the relay 163 will be operated.

The relay 163 now being operated attracts its armatures and switching circuits to be described. The contacts 162 will be 35 broken, but this will be for the time without effect since the now closed contacts 167 of the relay 164, are as has been described connected in multiple therewith. The contacts 191 of the relay 163 being closed likewise 40 will be without effect since the contacts 168 of the relay 164 in the circuit of the conductor leading from the contacts 191 are as has been described, previously broken. The contacts 184 of the link circuit trunk bar 169 45 also having been closed will complete a locking circuit from the ground pole of battery thru the now closed contacts 184, contacts 192 of the relay 163, and a locking winding 193 of the relay 163, to the negative pole of 50 the source of current. This locking circuit for the relay 163 having been completed the said relay will remain operated until the end of the conversational period, when as 55 will be described, the contacts 184 will be again opened restoring the relay 163 to its normal position.

The contacts 150 of the relay RIS of Fig. 4 being broken in the circuits of the relays XR and IMP will cause the armatures of 60 these relays and the apparatus controlled thereby in the dialling circuit to be restored to normal. The contacts 212 of the relay IMP being now restored to their normal position and the contacts 77 in the circuit of 65 the slow releasing relay 78 being opened,

a circuit will be completed for the winding 50 of the relay 51 traced as follows: from the ground pole of battery, contacts 212 of the relay IMP, contacts 49 of the relay 78, the still closed contacts 52 of the relay 53, 70 the winding 50 of the relay 51, to the negative source of current. Current from the said source flowing over the said circuit will operate relay 51, which will attract its armatures closing contacts 213 and 214 in the 75 circuits of the restoring switch members for the dialling or setting-up circuit, RM for the connection switch of Fig. 2, and RMS for the connection switch of Fig. 3. These restoring magnets being energized thru the 80 said contacts the switches will be released and will immediately seek their restored or normal positions.

The contacts 160 of the relay RIS also being opened will open the circuit of the 85 energizing windings of the relays SIR of Fig. 4, and FLC and 164 of Fig. 1, as well as the energizing winding of the vertical magnet 165 of the link circuit, and the armatures of the said relays SIR, FLC and 164 will be restored to their normal positions. The relay 164 being of the slow-releasing type will 90 momentarily retain its armatures for a function now to be described.

The contacts 194 of the relay 164 and the 95 contacts 195 of the relay 163 now being closed, a circuit will be completed from the ground pole of battery, thru the said contacts, thru the winding of the relay 196, the 100 normal contacts 197 of the relay 198, thru the now closed contact 199 of the relay 188, and the resistance coil 200 to the negative pole of the source of current. The closing of this circuit will cause a flow from the 105 said source of current thru the winding of the relay 196, operating the relay 196, and the said relay being operated a locking circuit will be completed for the same independent of the contacts 195 of the relay 163, and the contacts 194 of the relay 164. This 110 locking circuit is traced as follows: from the ground pole of battery, the contacts 215 of the relay 196, the winding of the said relay, the normal contacts 197 of the called subscriber's battery feed relay 198, and the 115 now closed contacts 199 of the calling subscriber's battery feed relay 188 thru the resistance coil 200, to the negative pole of the source of current. This circuit including the said source of current will hold the 120 relay 196, which is the ringing relay, operative to cause the ringing of the called subscriber's telephone bell, which bell will continue ringing until the response of the called-for subscriber. In the meantime the 125 relay 164 will have restored its armatures and their controlled apparatus to their normal positions of rest.

The apparatus of Figs. 2, 3 and 4 concerned in the establishment of the just de- 130

scribed function will now be restored to normal, the operation of the apparatus involved being briefly described as follows: The releasing relay 51 having been operated as previously described, a locking circuit for the said relay is thereby formed which may be traced from the ground pole of battery, thru the contacts 213 of the said relay, the locking winding 216 thereof, circuit conductor 47 of Fig. 4, leading therefrom to circuit conductor 47 of Fig. 2, the now closed contacts 217 of the vertical trunk bar V of the connection switch of Fig. 2, which trunk bar is associated with the setting-up circuit whose operation is being described, the circuit continued thru the said contacts 217 thru the winding of the release magnet RM, and the normally closed contacts 218 thereof to the negative pole of the source of current.

Connected in multiple with the said contacts 218, is the winding of the vertical bar release magnet N, which will be operatively connected in the said circuit upon the subsequent breaking of the contacts 218, which occurs only when the release magnet has fully operated its releasing bar, together with all of the associated restoring members N for the line bar of the switch of Fig. 2, which operation insures the full restoration to the latched position of the operated plug carriage which was originally displaced to contact operating position by the conjoint operation of the magnets 29 and VM previously described.

The operated plug carriage having been restored to normal position by the actuation of the restoring magnet RM, the contacts 218 will thereupon be opened to include the release magnet N in the operative circuit, so that it will un-latch the latching members 41, and the vertical trunk bar will thereupon be restored to its normal position. After it has practically acquired its normal position of rest, it opens the contacts 217, thus breaking the operative circuit of the electro-magnets RM and N of the connection switch, and also breaking the circuit of the locking winding 216 of the relay 51 of Fig. 4. The relay 51 is of the slow-releasing type and upon its having been opened, the connection switch of Fig. 3 will have also been restored to normal position.

This release occurs upon the closing of the contacts 214, completing a circuit from the ground pole of battery, thru the said contacts and over conductor 219 which is extended on Fig. 3, and leads thru the switch releasing magnet RMS, to the negative pole of the source of current. This causes the slow releasing magnet to attract its armature removing the retaining pawl from the teeth of the stepping wheel WH, and also causes the closure of the contacts 220 in the circuit of the electromagnet MM of the

switch which will attract its armature, and which will withdraw its propelling pawl from the teeth of the stepping wheel WH, so that the shaft upon which the said stepping wheel is mounted together with the switch arm members 57 and 58 is rotated back to such a position that the switch arm 58 is removed from the off-normal contact ON and contacts with the normal contact NOR for a purpose to be described, and the switch arm member 57 takes the ultimate position where it makes contact with the contact 221 of the switch. The switch arm 58 engaging its normal contact NOR short circuits the winding of the relay 53, which relay thereupon slowly releases its armatures for opening their controlled circuits to restore the contained electroresponsive apparatus to normal.

The ground connection of the member 58 being removed from the off-normal contact ON, the circuit of the off-normal relay ONR of Fig. 4 will be opened, and it will allow its armatures to be restored to their normal positions.

The rotation of the shaft 56 of the switch of Fig. 3 to normal position is accomplished by a spring member SM in a way which is clear from the drawing.

The contacts 71, 72 and 73 of the off-normal relay control the circuits of all of the operated apparatus of Figs. 2, 3 and 4 now in operated position, and when these contacts are opened all of this operated apparatus will be immediately restored to normal by the opening of the circuits described in connection therewith.

The setting-up or dialling circuits illustrated in Figs. 2, 3 and 4 will now revert to the use of another calling line to which it may be now automatically connected in the manner described for the connection just described, only instead of the link circuit LK being seized for use by the operation of apparatus in the said setting-up circuit by the extending of the conductors 161 and 207 leading from the said setting-up circuits to the said link circuit, thru contacts 191 and 222 of the relay 163 to conductors 223 and 224 leading to the apparatus of the next succeeding link circuit LK², the said next succeeding link circuit will be instead seized for use, or if in the meantime it has been seized for use by another dialling circuit connected to the said conductors 161 and 207 at the points 225 and 226, the next succeeding idle link circuit may be taken for use.

At this time it may be pointed out, although it should be apparent from the foregoing description that the conductors 161, 207, 227, 228, 229, 147 and 121 of Fig. 1, may be connected to by any of the setting-up or dialling circuits of the exchange, the connection being made at the points 225, 226, 230, 231, 232, 233 and 234.

The setting-up circuits and mechanisms having been discharged from the connection, the connection functions performed by the link circuit LK continue as follows:

5 The ringing relay 196 being operated, the ringing generator 235 will be connected thru the lamp 236 and contacts 237 and 238 of the relay 196, to the line wires of the called line, the connection being extended 10 thereto by means of the closed contacts 178, 181, 176 and 179 of the connection switch of Fig. 1, and circuit conductors which are directly connected to the line wires 241 and 242 leading to the subscriber's substation 15 telephone bell 243.

The called subscriber responding to the ringing of the bell by taking his receiver from the hook, will cause a flow of current superposed with the alternating ringing current 20 passing over the line from the source of direct current 243, and the said source of current flowing thru the ringing trip relay 249 will cause it to operate to close its contacts 245 long enough to produce the de- 25 energization of the relay 196 by short circuiting the relay, the deenergization of this relay being accompanied by the opening of the contacts 215 in the locking circuit of the relay so that the relay will be unlocked and 30 restored to its normal position. The ringing generator contacts 237 and 238 will also be opened disconnecting the ringing generator from the line.

The contacts 246 and 247 will now be re- 35 stored to their normally closed positions connecting the talking conductors 241 and 242 thru the connection switch contacts to the talking strands 248 and 249 of the link circuit, the talking strands being thereby connected thru the said link circuit talking strands, and the calling line connection switch contacts to the line conductors 13 and 14 of the calling line. The two subscribers are now united for conversational purposes 45 and the conversational period will now begin.

When the contacts 247 and 246 of the relay 196 were closed, the called line battery feed relay 198 was operated thru the said contacts and over the called subscriber's line and the contacts in the circuit of the ringing relay 196 was opened, so that this relay cannot again be operated during the conversational period regardless of the correct or in- 50 correct operation of other apparatus.

The subscribers upon finishing their conversation restore their receivers to the hook to perform the disconnect function. When the calling subscriber's receiver has been re- 60 stored to the hook, thus opening the line conductors at the contacts 15 at the substation A¹, the battery feed relay 188 for the said substation will be deenergized and its armatures will be restored to normal position, the contacts 187, 199 and 202 thereof

will be opened, and the contacts 203 of the said relay will be closed completing a circuit for the release magnet RM which is better illustrated in Figs. 5 to 8 inclusive; the circuit being traced as follows: from the 70 negative pole of the source of current, the plug carriage restoring magnet RM, the now closed contacts 252 associated therewith, and the winding of the vertical bar release magnet 183 in multiple with the said contacts and short circuited thereby, the contacts 254 of the relay 163, the normally closed contacts 203 of the relay 188, the now closed contact 184 of the trunk bar 169, to the ground pole of battery. 80

This will cause the operation of the plug carriage restoring magnet RM, and it will thereupon operate to restore the calling and called plug carriages of the connection switch illustrated in Fig. 5 from their contact closing positions to their normal positions, and the connection switch contacts 172-175, 171-174, 170-173, of the calling line and the connection switch contacts 178-181, 177-180 and 176-179, of the 90 called line will be opened.

Upon the full restoring of the above said plug carriages to normal position, the contacts 252 associated with the electromagnet RM will be opened, removing the short circuit thereby placed about the winding of the release magnet 183, and the release magnet 183 will thereupon become operated to unlatch the latch members 182 for the trunk bar 169, corresponding to the trunk bar V 100 of Fig. 5, and the same will thereupon be lifted under the control of its propelling spring to normal position.

The vertical bar having practically attained its normal position, will open the 105 contacts 184 controlled by the said vertical bar, and the opening of these contacts will release the relay 163 by opening the circuit of its holding winding 193. The opening of the contacts 184 will also open the energizing circuit for the release and restoring magnets 183 and RM, and the connection switch link circuit LK will be restored to 110 normal position.

The opening of the circuits of the calling 115 and called line cut-off relay magnets 25 and 122 by the opening of the connection switch contacts 171-174, and 177-180 will restore these cut-off relays to their normal position.

The relays 163 being restored will restore 120 the apparatus controlled thereby, as will the other released relays and magnets whose release has been described, and thus all of the apparatus concerned in the connection will be restored to normal position and to a condition where it may be again taken for use by a subsequent calling line.

The operation of the circuits and apparatus of my invention has been described 125 for a condition wherein the called line was 130

found "not busy" by the testing apparatus of the setting-up circuits shown in Fig. 4.

Now going back to that point of the description where the testing function was performed, we will assume that the called line is found to be busy by the apparatus provided for the testing function in the circuits of Figs. 3 and 4. The operation of the apparatus involved under such a condition 10 will now be described.

It has been described how a busy line is characterized by the presence of a ground connection in the circuit side of one of the line magnets associated with the line. This 15 ground connection would cause the operation as had been described of the line magnet, and it would therefore cause a ground connection to be placed on the conductor, such as the conductor 121 of the called line, such as the line 32 which in this description is assumed to be the called line; the ground being either placed on the conductor 121 by the contacts 274 of the line relay magnet 123 should the relay 123 be operated to cause 20 the busy test or will be placed by the interconnecting link circuit, such as the link circuit LK associated with the called line to cause it to be busy, a conductor of the link circuit, such as the conductor 201 conveying the ground connection thru the relay 204, thru the said link circuit, thru contacts 177-180 of the connection switch contacts of Fig. 1 in use by the said line to the circuit side of the winding of the line relay magnet 122 of the called line.

In any event the ground connection being made to conductor 121 characterizes the line associated with the said conductor 121, which is the line 32 in this description as a 40 busy line, and the busy test having been made the presence of this ground connection causes the said line to test busy; the testing function being described in detail as follows:

45 Referring back to the foregoing description, a circuit was caused to be completed upon the second actuation of the subscriber's dial including the switch arm 57 and the contact 106 of the switch of Fig. 3, the said circuit being traced as follows: from the negative pole of the source of current thru the winding of the busy test relay BT shown on Fig. 4, contacts 101 of the relay PD which are now closed, normal contacts 82 of the relay NB, normal contacts 76 of the relay INT, circuit conductor 80 which being extended on Fig. 3 leads to the switch arm 57 of the switch RS, the contact 106, circuit conductor 118, circuit conductor 119, the now closed contacts 120 of the digital relay DL³, circuit conductor 121 which being extended on Fig. 4 leads therefrom to the conductor switch of Fig. 1 and is connected to one side of the winding of the line magnet 122, the other side of the said winding being

connected to the negative pole of battery. This circuit being completed there will be no flow of current over the same if the called-for line is not busy, the called-for line 32 however being busy there will be a flow 70 of current from the ground connection to the circuit conductor 121, thru the busy test relay BT, operating the said busy test relay BT which will thereupon attract its armature, breaking contacts 131 in the circuit of 75 the relay NB to prevent its operation, closing contacts 257, and completing a circuit traced as follows: from the ground pole of battery, thru the contacts 102 of the relay PD, contacts 75 of the relay INT, the contacts 104 of the relay 103, the contacts 257 of the relay BT, the winding of the relay BB, to the negative pole of the source of current.

This circuit is only completed after the 85 contacts 104 have been restored to normal and after an interval has elapsed in which, as has been described, should the called line be available for use it may be taken for use, and the "busy" apparatus now being described disabled by the opening of the contacts 82 of the relay NB. Should the disabling of the busy apparatus not occur prior to the closing of the contacts 104, this is because of the operation of the busy test relay 90 BT, indicating a busy condition of the line, and the contacts 131 of the relay BT are opened in the circuit of the relay NB to prevent the relay NB functioning, as before described, to cause the connective operations. 100

The relay BB having operated it will close its contacts 281 and 282, the contacts 281 locking the relay BB in its operated condition, the locking circuit being traced from the negative pole of battery, thru the 105 winding BB, thru the contacts 281, the contacts 71 of the relay ONR to the ground pole of battery. The contacts 282 being operated completes a circuit for the busy tone current generator, said circuit including the 110 subscriber's telephone to produce a characteristic tone in the said subscriber's receiver to apprise the said subscriber of the busy condition of the called-for line. The circuit of this busy tone is traced from the 115 source of current, thru the usual busy apparatus BTD of Fig. 1 over the conductor 227 of Fig. 1 which is extended therefrom to the circuit conductor 227 of Fig. 4, thru contacts 282 of the relay BB to the conductor 45, which as has been described, leads thru the connection switch of Fig. 2, over the subscriber's line conductor 14, the subscriber's telephone A¹ returning to ground at the central station by means of line conductor 13, shown in Fig. 1. The subscriber upon being apprised of the busy condition of the called-for line will restore his telephone receiver to the hookswitch, breaking the contacts 15 of the said hookswitch in 120 125 130

the circuit of the relay IMP of Fig. 4, which relay will restore its armatures to normal position opening the contacts 54, 61 and 77, and closing the contacts 212. The circuits will now be restored to normal by the operation of these contacts in the manner which has been previously described in the description of the restoring of the setting-up apparatus by the deenergization of the relay IMP, when the said relay in the said description was restored after the connection period.

I am aware that many modifications may be made in the system of my invention, that various parts thereof may take varying forms without departing from the spirit of the invention. Such modifications will be apparent to those skilled in the art and are considered within the purview of the following claims:

1. In an automatic telephone system, the combination with a plurality of lines, a called line switching mechanism for each of the said lines, calling line switching mechanism for each of the lines associated with said called mechanism in a unitary switch structure, and means controlled by the calling line apparatus of a calling line to simultaneously operate the calling and called line switching apparatus of the calling and called lines, whereby the said switching apparatus is operated to interconnect said lines.

2. In an automatic telephone system, the combination with a plurality of lines, calling and called line switching mechanisms for each of the lines, a plurality of interconnecting link circuits for the said lines, the said calling line mechanism, the said called line mechanism and the said link circuits being connected in a unitary switch structure, and means controlled by the calling apparatus of a calling line to simultaneously operate the calling and called line switching apparatus of the calling and called lines, and to select an idle link circuit associated with the said calling and called line switching apparatus, whereby the said link circuit interconnects the said lines.

3. In a selector switch, the combination with a step-by-step contact making member, of contacts therefor, of a plurality of circuits adapted to be associated with the said contacts, the said circuits being larger in number than the said number of contacts, and relay means responsive upon a first actuation of the said member to associate a group of circuits with the next succeeding contacts of the said member whereby any one of the group may be selected by the said step-by-step contact making member upon the succeeding actuation thereof.

4. In a telephone system, a plurality of telephone lines, non-numerical switching mechanism associated with said lines, a plu-

rality of trunks terminating at both ends in 65 said non-numerical switching mechanism, each of the two sides of each trunk having its ends inductively connected together but conductively separated, and means controlled by one or more series of impulses of the same 70 character transmitted over the two sides of a calling telephone line in series including said non-numerical switching mechanism for connecting said calling telephone line and a called telephone line to the opposite ends of a 75 selected trunk.

5. In a telephone system, a plurality of telephone lines, non-numerical switching mechanism for said lines, a plurality of trunks, each of said trunks terminating at 80 each end in trunk terminals of said non-numerical switching mechanism, certain of said trunk terminals being conductively separated but inductively connected together, and means controlled by one or more series of im- 85 pulses of the same character transmitted over the two sides of a calling telephone line in series for causing the non-numerical switching mechanism to connect said calling telephone line and a called telephone line to 90 opposite ends of an idle one of said trunks.

6. In a telephone system, a plurality of telephone lines, said lines being provided with a trunk selecting mechanism, a plurality of trunks, a plurality of register senders, means for connecting a register sender to a calling telephone line upon the initiation of a call, means for variably adjusting said connected register sender in accordance with the designation of a called line by means of one or more series of impulses of the same 100 character transmitted over the two sides of said calling telephone line, means effected by the setting of said register sender for causing the calling and called telephone line to 105 be connected to a trunk line by said trunk selecting mechanism, and means operative thereafter but before the termination of a call for restoring said register sender to common use.

7. In a telephone system, a plurality of telephone lines, a plurality of trunk circuits, means including non-numerical switching means for connecting a calling and a wanted telephone line to the opposite ends of a 115 trunk circuit, a plurality of register senders each including a stepping switch and a plurality of multi-contact relays, each of said relays being individual to a group of lines, means for variably adjusting said register sender in accordance with impulses trans- 120 mitted over said calling line, means controlled by the setting of said stepping switch and the actuation of one of said multi-contact relays for effecting the operation of the non-numerical switching means to connect the calling and the wanted line to an idle trunk, and means operative thereafter but 125

before the termination of a call for restoring the operated register sender to common use.

8. In a telephone system, a plurality of telephone lines, a plurality of trunk circuits, a plurality of register senders, means for preselecting register senders for use, means for connecting a preselected register sender to a calling telephone line, means controlled by impulses over said calling telephone line to variably adjust said register sender in accordance with the designation of a wanted telephone line, means for preselecting trunk circuits for use and switching mechanism associated with the calling and called telephone lines and controlled by said register sender for connecting a calling and a called telephone line to a preselected trunk circuit.
9. In a telephone system, a plurality of telephone lines, a plurality of trunk circuits, a plurality of register senders, means for preselecting register senders for use, means for connecting a preselected register sender to a calling telephone line, means controlled by impulses over said calling telephone line to variably adjust said register sender in accordance with the designation of a wanted telephone line, means for preselecting trunk circuits for use and switching mechanism associated with the calling and called telephone lines and controlled by said register sender for connecting a calling and a called telephone line to a preselected trunk circuit, and means for releasing the adjusted register sender for common use before the termination of the connection.
10. In a telephone system, a plurality of telephone lines, a plurality of trunk circuits, a plurality of register senders, means for preselecting register senders for use, means for connecting a preselected register sender to a calling telephone line, means controlled by impulses over said calling telephone line to variably adjust said register sender in accordance with the designation of a wanted telephone line, means for preselecting trunk circuits for use, switching mechanism associated with the calling and called telephone lines, and controlled by the adjusted register sender for connecting the calling and called telephone line to the preselected trunk circuit subsequent to the seizure of said adjusted register sender.
11. In a telephone system, a plurality of telephone lines, a plurality of trunk circuits, a plurality of register senders, means for preselecting register senders for use, means for connecting a preselected register sender to a calling telephone line, means controlled by impulses over said calling telephone line to variably adjust said register sender in accordance with the designation of a wanted telephone line, means for preselecting trunk circuits for use, and switching mechanism associated with the calling and called tele-

phone lines and controlled by the adjusted register sender for connecting the calling and called telephone line to the preselected trunk circuit subsequent to the seizure of said adjusted register sender, and means for releasing the adjusted register sender for common use prior to the termination of the connection.

12. In a telephone system, a plurality of telephone lines, switching means common to said telephone lines, a plurality of trunks each terminating in terminals in said switching means, certain of said terminals being calling terminals used exclusively in extending a call from a telephone line and others of said terminals being called terminals used exclusively in extending calls to a telephone line, and means controlled by one or more series of impulses of the same character transmitted over the two sides of a calling telephone line in series for causing said switching means to connect a calling line to the calling terminals of a trunk line and for causing said switching means to connect the called line to the called terminals of the same trunk circuit.

13. In a telephone system, a plurality of telephone lines, a plurality of trunks, means for allotting trunks for use, a plurality of register senders, means for allotting a register sender for use, means controlled over a calling one of said telephone lines for variably adjusting the allotted register sender in accordance with the designation of a wanted telephone line, and non-numerical switching mechanism associated with said telephone lines and arranged to be operated under the control of said register sender, to connect the calling and wanted telephone lines through an allotted trunk.

14. In a telephone system, a plurality of telephone lines, a plurality of trunks, means including an extended starter wire arrangement for allotting trunks for use, a plurality of register senders, means for allotting register senders for use, means controlled over a calling one of said telephone lines for variably adjusting the allotted register sender in accordance with the designation of a wanted telephone line, and non-numerical switching mechanism associated with said telephone lines and arranged to be operated under the control of said register sender, to connect the calling and wanted telephone lines through an allotted trunk.

15. In a telephone system, a plurality of telephone lines, a plurality of trunks, means for allotting trunks for use, switching means for connecting a calling and a wanted telephone line to an allotted trunk, a plurality of register senders each including a progressively movable stepping switch responsive to directive impulses transmitted over a calling telephone line, test circuits, one for each telephone line arranged to be completed

through said stepping switch, and a plurality of multi-contact relays, each controlling several of said test circuits, the operation of said switching means to connect a calling and a wanted telephone line to an allotted trunk being initiated by said register sender over a test circuit individual to the wanted telephone line.

16. In a telephone system, a plurality of telephone lines, a plurality of link circuits, automatic switching means for said telephone lines, fixed terminals for said automatic switching means in which both ends of each link circuit terminates, sections of each link circuit determined by inductive means, sources of talking battery connected to said sections, and means for causing said automatic switching means to connect a calling and a wanted telephone line to a link circuit.

17. In a telephone system, a plurality of telephone lines, a plurality of trunks, automatic switching means for interconnecting calling and called telephone lines, a plurality of call storing devices arranged to be simultaneously adjusted over calling telephone lines, and means for causing said switching means to connect sets of calling and called telephone lines, one set at a time under the control of a related call storing device.

18. In a telephone system, a plurality of telephone lines, automatic switching means for said lines having wipers and fixed contacts, trunk circuits terminating at each end in said fixed contacts, said trunk circuits being divided into two sections by condensers, and means for connecting a source of talking battery to each of said sections.

19. In a telephone system, an incoming circuit, a plurality of outgoing circuits arranged in groups, an automatic switch for interconnecting said incoming circuit with any one of said outgoing circuits to the exclusion of said other outgoing circuits, said automatic switch being provided with a wiper and contacts serving as terminals for all of said outgoing lines terminating thereat, the number of said contacts being less than the number of outgoing circuits.

20. In a telephone system, an incoming circuit, a plurality of outgoing circuits arranged in groups, an automatic switch for interconnecting said incoming circuit with any one of said outgoing circuits, said automatic switch being provided with a wiper and contacts serving as terminals for all of said outgoing circuits, the number of said contacts being less than the number of said outgoing circuits terminating at said switch, and means for isolating a selected outgoing circuit from the remaining outgoing circuits.

21. In a telephone system, an incoming circuit, a plurality of outgoing circuits arranged in groups, a switch having a wiper

in which said incoming line terminates, and contacts to be engaged thereby arranged in the same plane, said outgoing lines terminating in said contacts, means for advancing said wiper the same distance over said contacts in response to group and line selecting impulses.

22. In a telephone system, an incoming circuit, a plurality of outgoing circuits arranged in groups, a switch having a single set of wipers in which said incoming line terminates and contacts to be engaged thereby arranged in the same plane, said outgoing circuits terminating in said contacts, and means for advancing said wipers the same distance over said contacts in response to group and line selecting impulses.

23. In a telephone system, an incoming circuit, a hundred outgoing circuits, an automatic switch having fixed contacts and a wiper co-operating therewith, said switch having twenty fixed contacts in which said one hundred outgoing circuits terminate, and means for selecting and isolating from the remaining outgoing circuits any one of the hundred outgoing circuits to which said incoming circuit is extended.

24. In a telephone system, an incoming circuit, one hundred outgoing circuits, an automatic switch for interconnecting said incoming circuit with any one of said one hundred outgoing circuits, said automatic switch having twenty contacts in which said one hundred lines terminate, and a wiper in which said incoming line terminates, and means including multi-contact relays co-operating with said automatic switch to isolate from the remaining outgoing circuits an outgoing circuit to which said incoming circuit has been extended.

25. In a telephone system, a register sender including a rotary switch having contacts and wipers co-operating therewith, said rotary switch being responsive to group and line selecting impulses transmitted from a distant point, a plurality of multi-contact relays in the contacts of which distinct groups of outgoing lines are segregated, means including said rotary switch for selectively actuating one set of multi-contact relays to segregate a group of lines, and means for selectively operating said rotary switch to select and isolate a line in the selected group.

26. In a telephone system, a selective switch having a plurality of contacts spaced at substantially equal distances apart and a wiper co-operating therewith, lines terminating in said terminals, means operating in response to groups of impulses from a distant point to advance said wiper from one contact to the next in a step-by-step movement for associating a group of lines with a plurality of the next succeeding terminals.

27. In a telephone system, an automatic switch provided with a plurality of contacts and a wiper co-operating therewith, lines terminating in said contacts and an incoming circuit terminating in said wiper, means outside of said switch for segregating said lines into groups, means responsive to group and line impulses transmitted from a distant point for operating said wiper to extend said incoming line, and means responsive to the group operation of said wiper for actuating said segregating means.
28. In a selective switching system, a row of contacts, a movable contact maker for engaging the said contacts, means to propel the said movable contact maker along the row of contacts, an electromagnet for each of the said contacts energized when the movable contact maker stops in engagement with the said contact, and an electric switch under the control of the said electromagnet for changing the circuit connections for next succeeding contacts adapted to be subsequently engaged upon a subsequent continued movement of the said contact maker.
29. In a selective switching system, a row of equidistant contacts, a movable contact maker for engaging the said contacts, means to propel the said contact maker along the row of contacts to first select a line group, and means responsive to the said first selection to provide a group of the next succeeding contacts with line connections of the said group, whereby the said contact maker in its succeeding continued movement along the said row of contacts may select a line of the said group.
30. In a selective switching system, a plurality of selectable lines therefor arranged in groups, a plurality of line contacts, a movable contact maker for the said contacts, propelling means for the said contact maker, electromagnetic means for each of the said contacts, circuit connections and a source of current to energize the electromagnet associated with a given contact when the said movable contact maker remains in engagement with said contact longer than the contact passing interval, and an electric switch under the control of the said operated electromagnet for changing the circuit connections for next succeeding contacts of a group of lines adapted to be traversed upon a subsequent continued movement of the said contact maker along the row of contacts, whereby the said contact maker upon subsequently stopping in engagement with one of the contacts of the group may select a particular line of a group of the said selectable lines.
31. In a telephone system, a plurality of telephone lines, switching mechanism, a plurality of trunk circuits, means for allotting trunk circuits for use, a plurality of register senders, means for allotting a register sender for use, means controlled from a distant point for variably operating an allotted register sender in accordance with the designation of a called telephone line, and means for simultaneously operating such switching mechanism under the control of the register sender for connecting a calling telephone line and a called telephone line to an allotted trunk circuit.
32. In a telephone system, a plurality of telephone lines, switching mechanism, a plurality of trunk circuits, means for allotting trunk circuits for use, a plurality of register senders, means for allotting a register sender for use, means controlled from a distant point for variably operating an allotted register sender in accordance with the designation of a called telephone line, means for simultaneously operating such switching mechanism under the control of the register sender for connecting a calling telephone line and a called telephone line to an allotted trunk circuit, and means for restoring the operated register sender to common use prior to the termination of a connection.
33. In an automatic telephone system, a plurality of incoming circuits, non-numerical switching means associated with said incoming circuits, a plurality of trunks terminating at both ends in said non-numerical switching means, each of the two sides of each trunk having its ends inductively connected together but conductively separated and means controlled by one or more series of impulses transmitted over the two sides of one incoming circuit in series including non-numerical switching means for interconnecting said last mentioned incoming circuit to a second incoming circuit over one of said trunks.
34. In a telephone system, a plurality of incoming circuits, non-numerical switching means associated with said incoming circuits a plurality of trunks terminating at both ends in said non-numerical switching means, each of the two sides of each trunk having its ends inductively connected together but conductively separated, a test circuit for each incoming circuit, means controlled over the two sides of one incoming circuit in series for completing a test circuit of a wanted incoming circuit, and means including a completed test circuit of the wanted incoming line for causing said switching means to interconnect said first mentioned incoming circuit and said wanted incoming circuit over one of said trunks.
35. In a telephone system, a plurality of incoming circuits, non-numerical switching means associated with said incoming circuits a plurality of trunks terminating at both ends in said non-numerical switching means, a test circuit for each incoming circuit, a rotary switching device, a plurality of multi-contact relays, means controlled over the two sides of an incoming circuit in

- series for variably and selectively actuating said rotary switch and multi-contact relays to complete the test circuit of a wanted incoming circuit and means including said 5 non-numerical switching means actuated in response to the completion of a test circuit, for interconnecting said first-mentioned incoming circuit and a wanted incoming circuit.
- 10 36. In a telephone system, a plurality of telephone lines, a plurality of trunks, non-numerical switching means for interconnecting said lines and trunks, a test circuit for each telephone line, a plurality of break points in each test circuit, means responsive to directive impulses over a calling telephone line for closing one break point in the test circuit of a wanted telephone line, and means responsive to a second series of impulses over the calling telephone line for completing a second break point in the test circuit of the wanted telephone line, said test circuit on completion operating to cause said switching means to interconnect a calling telephone line and a wanted telephone line over a trunk.
- 15 37. In a telephone system, a plurality of telephone lines, a plurality of trunks, non-numerical switching means for inter-connecting said lines and trunks, a rotary switch, a plurality of multi-contact relays controlled by said rotary switch, a test circuit for each telephone line, a break point in each test circuit, controlled by a multi-contact relay, and means responsive to directive impulses over a calling telephone line for operating said rotary switch and one of said relays to close a break-point in the test circuit of a wanted telephone line, said test circuit on completion operating to cause said switching means to interconnect a calling telephone line and a wanted telephone line over a trunk.
- 20 38. In a telephone system, incoming lines, transfer circuits, outgoing lines, separately movable switching mechanisms for connecting said incoming lines to said transfer circuits, separately movable switching mechanisms individual to each of said transfer circuits for connecting them to said outgoing lines, magnets for said switching mechanisms, and means including bars for cooperating with said magnets to actuate a plurality of said switching mechanisms whereby said incoming lines may be extended through said transfer circuits to said outgoing lines, said bars also acting to maintain said mechanisms throughout the connection.
- 25 39. In a telephone system, incoming lines, transfer circuits, an outgoing line, switching mechanisms to connect said outgoing line to said incoming lines through said transfer circuits, an actuating bar for rendering said switching mechanisms operative, and a mag-
- net individual to each of said switching mechanisms to actuate said switching mechanisms when made operative by said actuating bar.
40. In a telephone system, incoming lines, transfer circuits, outgoing lines, separately movable switching mechanisms for connecting said incoming lines to said transfer circuits, separately movable switching mechanisms for connecting said transfer circuits to said outgoing lines, magnets for said switching mechanisms, and bars for cooperating with said magnets to actuate a plurality of said switching mechanisms whereby said incoming lines may be extended through said transfer circuits to said outgoing lines.
- 45 41. In a telephone system, incoming lines, transfer circuits, outgoing lines, separately movable switching mechanisms for connecting said incoming lines to said transfer circuits, separately movable switching mechanisms for connecting said transfer circuits to said outgoing lines, magnets for said switching mechanisms, and bars cooperating with said magnets to simultaneously actuate a plurality of said switching mechanisms whereby said incoming lines may be extended through said transfer circuits to said outgoing lines.
- 50 42. In a telephone system, incoming lines, transfer circuits, outgoing lines, separately movable switching mechanisms for connecting said incoming lines to said transfer circuits, separately movable switching mechanisms for connecting said transfer circuits to said outgoing lines, magnets for said switching mechanisms, and bars cooperating with said magnets to selectively actuate a plurality of said switching mechanisms whereby said incoming lines may be extended through said transfer circuits to said outgoing lines.
- 55 43. In a telephone system, incoming lines, transfer circuits, outgoing lines, separately operable switching mechanisms for connecting said incoming lines to said transfer circuits, separately operable switching mechanisms for connecting said transfer circuits to said outgoing lines, incoming line magnets each having control over a plurality of said first mentioned switching mechanisms, outgoing line magnets each having control over a plurality of said latter switching mechanisms, bars cooperating with said magnets whereby a single one of said mechanisms controlled by each of said magnets may be actuated in conjunction with such of said magnets as are actuated, and means for simultaneously operating an incoming line magnet and an outgoing line magnet to connect an incoming line through a transfer circuit to an outgoing line.
- 60 44. In a telephone system, incoming lines, transfer circuits, outgoing lines, separately

operable switching mechanisms for connecting said incoming lines through said transfer circuits to said outgoing lines, incoming line magnets, outgoing line magnets, actuating

5 bars operated by said magnets, magnets for rendering said bars effective to actuate switching mechanisms, and means for simultaneously operating an incoming line magnet and an outgoing line magnet to actuate said 10 switching mechanisms to connect the incoming line through a transfer circuit to an outgoing line.

45. In a telephone system, incoming lines, transfer circuits, outgoing lines, separately 15 movable switching mechanisms for connecting said incoming lines to said transfer circuits, separately movable switching mechanisms individual to each of said transfer circuits for connecting them to said outgoing 20 lines, magnets for said switching mechanisms, and bars for cooperating with said magnets to actuate a plurality of said switching mechanisms whereby coexisting connections may be extended from said incoming lines through said transfer circuits to said outgoing lines.

46. In a telephone system, incoming lines, transfer circuits, outgoing lines, separately movable switching mechanisms for connecting 30 said incoming lines to said transfer circuits, separately movable switching mechanisms individual to each of said transfer circuits for connecting them to said outgoing lines, magnets for said switching mechanisms; and bars cooperating with said magnets to simultaneously actuate a plurality of said switching mechanisms whereby coexisting connections may be extended from said incoming lines through said 35 transfer circuits to said outgoing lines.

47. In a telephone system, incoming lines, transfer circuits, outgoing lines, separately movable switching mechanisms for connecting said incoming lines to said transfer circuits, separately movable switching mechanisms individual to each of said transfer circuits for connecting them to said outgoing lines, magnets for said switching mechanisms, and bars cooperating with said magnets to selectively actuate a plurality of said switching mechanisms whereby coexisting connections may be extended from said incoming lines through said transfer circuits to said outgoing lines.

48. In a telephone system, incoming lines, transfer circuits, an outgoing line having multiple contacts corresponding to said transfer circuits, separately movable switching mechanisms, incoming line magnets, an outgoing line magnet, a single operating magnet for each of said transfer circuits, and means to operate an incoming line magnet, a transfer circuit magnet and an outgoing line magnet to actuate a plurality of

said switching mechanisms to extend an incoming line through a transfer circuit to said outgoing line.

49. In a telephone system, incoming lines, transfer circuits, outgoing lines, separately movable switching mechanisms for connecting said incoming lines to said transfer circuits, separately movable switching mechanisms individual to said transfer circuits for connecting them to said outgoing lines, magnets for said switching mechanisms and bars for cooperating with said magnets to actuate a plurality of said switching mechanisms whereby said incoming lines may be extended through said transfer circuits to said outgoing lines.

50. In a telephone system, incoming lines, transfer circuits, outgoing lines, separately movable switching mechanisms for connecting said incoming lines to said transfer circuits, separately movable switching mechanisms individual to said transfer circuits for connecting them to said outgoing lines, and a plurality of bars for controlling and operating said switching mechanisms, certain of said bars maintaining said switching mechanisms in operation independently of mechanical connection to said other bars which assisted in the operation of said mechanisms.

51. In a telephone system, incoming lines, transfer circuits, outgoing lines, separately movable switching mechanisms for connecting said incoming lines to said transfer circuits, separately movable switching mechanisms individual to said transfer circuits for connecting them to said outgoing lines, bars for preparing said switching mechanisms for operation, other bars cooperating mechanically with said first bars for causing and maintaining the operation of said prepared switching mechanisms, and means for returning said first bars to a normal position independent of any mechanical connection with said operated switching mechanisms.

52. In a telephone system, incoming lines, transfer circuits, outgoing lines having multiple contacts corresponding to said transfer circuits, separately movable switching mechanisms, incoming line bars, outgoing line bars, and bars cooperating with said line bars to actuate and maintain actuated said switching mechanisms to extend said incoming lines through said transfer circuits to said outgoing lines, said switching mechanisms being maintained in operated condition independently of said line bars.

53. In a telephone system, incoming lines, transfer circuits, outgoing lines having multiple contacts corresponding to said transfer circuits, separately movable switching mechanisms, incoming line bars, outgoing line bars, and bars cooperating with said

- line bars to actuate and maintain in actuated condition said switching mechanisms to extend said incoming lines through said transfer circuits to said outgoing lines, said 5 switching mechanisms being maintained in operated condition independently of any mechanical connection with said line bars.
54. A series of line switches, devices common to and controlling the series of line 10 switches, a motor connected to each device for moving it, and interconnections for causing a plurality of motors to operate simultaneously.
55. The combination in a switching system of incoming lines, link circuits and outgoing lines, with means for establishing line-link-line connections comprising fixed conducting elements constituting said link circuits, a set of incoming line contacts, a set 20 of outgoing line contacts and means for simultaneously moving said sets of contacts to engage said fixed conducting elements.
56. In a telephone system, telephone lines, a line relay, a line bar, and a combined line 25 bar magnet and cut-off relay associated with each line, trunk lines for extending said lines, a trunk bar, a trunk bar magnet and an auxiliary relay associated with each trunk, an allotter circuit for said trunks independent of said line relays and said combined line bar magnets and cut-off relays for placing idle trunks in condition for seizure by said lines through the agency of said line and trunk bars, and means for directly controlling said allotter circuit over said line and trunk bars.
57. In a telephone system, a cross-bar switch comprising a plurality of line bar magnets, a plurality of trunk bar magnets, 40 a relay associated with each of said trunk bar magnets, means controlled by said relays for holding one of said trunk bar magnets energized, means for energizing one of said line bar magnets, means controlled by said energized line bar magnet and said energized trunk bar magnet for energizing the relay associated with said trunk bar magnet.
58. In a telephone system, a cross-bar switch comprising a plurality of line bar 50 magnets, a plurality of trunk bar magnets, a relay associated with each of said trunk bar magnets, means controlled by said relays for holding a single one of said trunk bar magnets energized, and means controlled by said line bar magnets for energizing said relay associated with said energized trunk bar magnet.
59. In a telephone exchange system, a calling and a called subscriber's line, means for 55 extending said calling line, an impulse controlling mechanism to which said calling line is extended and which is common to said lines, relays simultaneously actuated by said impulse controlling mechanism for connect-
- ing said calling line to said called line, and 65 means under the sole control of the calling subscriber for releasing the established connection.
60. In a telephone exchange system, calling and called subscribers' lines, a relay mechanism individual to the calling line, a link circuit for joining said calling and called lines, an impulse controlling mechanism, switching means individual to said calling and called lines for connecting the same to 70 said link circuit, the operation of the switching means individual to the calling line being dependent upon certain electrical conditions at the relay mechanism individual to said calling line and at said impulse controlling mechanism, and the switching means individual to said called line being responsive only to an electrical condition at the impulse controlling mechanism, and means for operating the switching means individual to said calling and called lines.
61. In a telephone exchange system, calling and called subscribers' lines, a relay mechanism individual to the calling line, a link circuit for joining said calling and called lines, an impulse controlling mechanism, switching means individual to said calling and called lines for connecting the same to 75 said link circuit, the operation of the switching means individual to the calling line being dependent upon certain electrical conditions at the relay mechanism individual to said calling line and at said impulse controlling mechanism, and the switching means individual to said called line being responsive only to an electrical condition at the impulse controlling mechanism, and means for operating the switching means individual to said calling and called lines.
62. In a telephone exchange system, a calling and a called subscriber's line, means individual to said calling line for extending same, an impulse controlling mechanism to 90 which said calling line is extended and which is common to said lines, and relays actuated simultaneously for connecting said calling line to said called line, one of said relays being individual to the calling line and controlled by said impulse controlling mechanism and said individual means, and the other relay being individual to the called line and controlled only by said impulse controlling mechanism.
63. In a telephone system, telephone lines, link circuits, a trunk circuit, switching devices having permanently paired primary and secondary contacts for interconnecting said lines and said links and said trunk, means in said links under control of said lines for disconnecting a link from a line 100 and causing the connection of said trunk to

- a line, said means including contacts of a switching device employed in connecting a said line to a said link.
64. In a telephone system, a calling and a called line, means for establishing a by-path connection between said lines, and cross bar switches under control of said means for establishing a talking connection between said lines.
65. In a telephone system, a calling and a called line, means under control of said calling line for establishing a by-path connection between said lines, and cross bar switches under control of said means for establishing a talking connection between said lines.
66. In a telephone system, a calling and a called line, means for establishing a by-path connection between said lines, cross bar switches for extending said calling line to said means, and cross bar switches under control of said means for establishing a talking connection between said lines.
67. In a telephone system, a calling and a called line, means under control of said calling line for establishing a by-path connection between said lines, primary and secondary switches responsive to the initiation of a call on said calling line for extending said calling line to said means, and mechanical switching devices having permanently paired primary and secondary contacts under control of said means for establishing a talking connection between said lines.
68. In a telephone system, a calling and a called line, means for establishing a connection to said called line, mechanical switching devices having permanently paired primary and secondary contacts for extending a circuit from said called line under control of said first means, mechanical switching devices, having permanently paired primary and secondary contacts for extending a circuit from said calling line under control of said first means, and means for joining the circuits thus extended from said lines.
69. In a telephone system, a calling and a called line, means for establishing a by-path connection between said lines, cross bar switches under control of said means for establishing a talking connection between said lines and means responsive to the establishment of said talking connection for releasing said by-path connection.
70. In a telephone system, telephone lines, means comprising switching devices having permanently paired primary and secondary contacts for interconnecting said lines, control circuits independent of said contacts for controlling said devices, and a common sender for affecting said circuits to include a plurality of said devices in a connection.
71. In a telephone system, telephone lines, means for interconnecting said lines through a by-path connection, and switching devices having permanently paired primary and secondary contacts under control of said means for establishing a talking connection between said lines.
72. In a telephone system, calling and called telephone lines, a common sender under control of said calling telephone lines for extending a by-path connection to said called lines, and switching devices having permanently paired primary and secondary contacts for establishing talking connections between said calling and said called lines, said sender controlling and including a plurality of said devices in a connection.
73. In a telephone system, a calling telephone line, a called telephone line, a plurality of switches each having permanently paired primary and secondary contacts for extending said calling line to said called line, a sender accessible to said calling line for controlling said switches, and means in said sender responsive to the busy condition of said called line for transmitting a busy tone to said calling line.
74. In a telephone system, a calling telephone line, a called telephone line, a plurality of cross bar switches for extending said calling line to said called line, a sender accessible to said calling line for controlling said switches, and means in said sender responsive to the busy condition of said called line for transmitting a busy tone to said calling line.
75. The combination in a switching system of incoming lines, outgoing lines, contact sets for said incoming lines, contact sets for said outgoing lines, an operating mechanism common to said incoming lines, an operating mechanism individual to each outgoing line, other operating mechanisms associated in common with said first and second mentioned operating mechanisms, the conjoint operation of one of each of said first, second and third mentioned operating mechanisms being effective to actuate the contact sets of said incoming and outgoing lines to establish a connection between one of said incoming and one of said outgoing lines, said first mentioned operating mechanism being operable in conjunction with other of said second and third operating mechanisms to establish connections between other incoming and outgoing lines co-existing with the connection already established.
76. The combination in a switching system of incoming lines, link circuits and outgoing lines, with means for establishing line-link-line connections comprising a set of incoming line bars, a set of link bars and a set of outgoing line bars, and means for preventing the simultaneous operation of more than one bar of each of said sets.
77. The combination in a switching system of incoming lines, link circuits and out-

going lines, with means under the control of incoming lines for establishing line-link-line connections comprising a set of incoming line bars, a set of link bars and a set of outgoing line bars, and means to prevent interference between simultaneously calling incoming lines.

78. In a telephone exchange system, a selective switch, an incoming line, outgoing lines, said switch having a plurality of intermediate links for connecting the incoming line to the outgoing lines, and a separate link common to said intermediate links for testing the condition of the outgoing lines.

79. In a telephone exchange system, a selective switch, an incoming line, outgoing lines, said switch having a plurality of intermediate links for connecting the incoming line to the outgoing lines, means for selecting an idle intermediate link without establishing the connection, a separate link common to the intermediate links for testing the condition of the outgoing lines, and means for thereupon establishing the connection if the tested line is idle.

80. In a telephone exchange system, a selective switch, a plurality of incoming lines, outgoing lines, said switch having a number of intermediate link circuits for connecting the incoming lines to the outgoing lines, and a separate link common to said intermediate links for testing the condition of the outgoing lines.

81. In a telephone system, a selective switch, a plurality of incoming lines, outgoing lines arranged in groups, said switch having a plurality of intermediate links for connecting any incoming line to any outgoing line, and a separate link common to said intermediate links for testing the busy and idle conditions of the outgoing lines.

82. In a telephone exchange system, a

selective switch, an incoming line, outgoing lines, said switch having a plurality of intermediate links for connecting the incoming line to the outgoing lines, a selection controlling mechanism for operating said switch, and a separate link common to said intermediate links for testing the condition of the outgoing lines.

83. The combination, in a switching system, of incoming circuits, link circuits primarily accessible from said incoming circuits, outgoing circuits, contact sets, and a plurality of switching bars cooperating with each other for actuating said contact sets to connect an incoming circuit to a link circuit and to connect such link circuit to any available outgoing circuit.

84. The combination, in a switching system, of incoming circuits, link circuits primarily accessible from said incoming circuits, outgoing circuits, contact sets, and a plurality of intersecting switching bars acting jointly and cooperating with each other for actuating said contact sets to connect any incoming circuit with a link circuit and to connect such link circuit to any available outgoing circuit.

85. The combination, in a switching system, of incoming circuits, link circuits primarily accessible from said incoming circuits, outgoing circuits, contact sets, a plurality of switching bars cooperating with each other for actuating said contact sets to connect an incoming circuit to a link circuit and to connect such link circuit to any available outgoing circuit, and means for restoring one of said bars without releasing the established connection.

In witness whereof, I hereunto subscribe my name this 22nd day of December A. D. 1917.

FRANK M. SLOUGH.
